UNITED STATES PATENT OFFICE.

MARY KAVANAGH, OF NEW YORK, N. Y., ASSIGNOR TO THE BUTTERICK PUBLISHING COMPANY, (LIMITED,) OF SAME PLACE.

DESIGN FOR A GIRL'S COSTUME.

SPECIFICATION forming part of Design No. 15,633, dated December 23, 1884.

Application filed November 15, 1884. Term of patent 3½ years.

To all whom it may concern:

Be it known that I, MARY KAVANAGH, of the city, county, and State of New York, have invented and produced a new and original Design for a Pattern of a Girl's Costume, (numbered 9,530;) and I do hereby declare that the engraved prints accompanying this specification convey to any one accustomed to using paper patterns a clear understanding of how a garment made up by the pattern will appear.

The design shows narrow sack body-fronts that exhibit a closing all the way down, a box-plaited front skirt, a plaited scarf-drapery crossing the lower part of the body, a loose-fitting body-back exhibiting a gathered skirt, polonaise-fronts flaring from the tops of

the shoulders in deep points upon the front skirt, appearing to meet at the lower part of the center of the body-back, and disclosing 20 gatherings at the neck-edges and draping plaits in the back edges, coat-sleeves, and a deep turn-down collar rounding away from the throat

What I claim as my invention, and desire to 25 secure by Letters Patent, is—

The design for a girl's costume, as shown in the engraved prints accompanying this specification.

MARY KAVANAGH.
